UNITED STATES PATENT OFFICE.

ALBERT H. LEWIS, OF NEW COMERSTOWN, OHIO, ASSIGNOR OF ONE-THIRD TO WILLIAM F. PALMER AND ONE-THIRD TO MARION E. ALEXANDER, OF NEW COMERSTOWN, OHIO.

JOURNAL-BOX.

No. 895,096.

Specification of Letters Patent.

Patented Aug. 4, 1908.

Application filed June 26, 1907. Serial No. 380,893.

To all whom it may concern:

Be it known that I, ALBERT H. LEWIS, citizen of the United States, residing at New Comerstown, in the county of Tuscarawas 5 and State of Ohio, have invented new and useful Improvements in Journal-Boxes, of which the following is a specification.

My invention relates to journal boxes constructed with a view of lubricating shafts and 10 axles; and its novelty, utility and practical advantages will be fully understood from the following description and claims when the same are read in connection with the accompanying drawings, forming part of this specification, in which:

Figure 1 is a side elevation showing a shaft in proper position in my improved lubricating journal box. Fig. 2 is a transverse section taken in the plane indicated by the line 20 2—2 of Fig. 1, and showing the reservoir, the lubricant-conveying belt, the drum, the pressure roller, and the Babbitt-metal sections of my improvements. Fig. 3 is a transverse section taken in the plane of the line 3—3 25 of Fig. 1, looking in the direction of the arrow, and showing one of the lubricant filters of the improved journal box. Fig. 4 is a cross-section on the line 4—4 of Fig. 1 to show one of the lubricant retainers—i. e., one 30 of the devices for preventing lubricant from working out of the casing and for causing such lubricant to pass from the shaft to the bottom of the casing. Fig. 5 is a detail side elevation showing such lubricant retainer 35 properly arranged relative to the shaft. Fig. 6 is a detail side elevation showing the arrangement of the sections of Babbitt metal relative to the shaft. Fig. 7 is a plan view showing the recesses in the longitudinal edges 40 of the lower Babbitt metal section for the passage of the lubricant conveying belt. Figs. 8 and 9 are views of one filter, removed. Fig. 10 is a detail section showing the relative arrangement of the casing, one filter and 45 one door of the box.

Similar letters designate corresponding parts in all of the views of the drawings, referring to which:

A is a shaft, and B is the casing of the 50 journal box constituting the preferred embodiment of my present invention. The said casing B comprises a lower section *a* and an upper section *b*, and these sections are arranged as illustrated, relative to the shaft 55 A, and are hinged together at one side of the

shaft, as indicated by *b'*, and are detachably connected together at the opposite side of the shaft, preferably through the medium of bolts *c* extending through opposed apertured lugs *d* on the sections. The lower section *a* 60 of the casing is provided at an intermediate point of its length with a reservoir or well *e* for lubricant; and it is also provided with bottom portions *f* which are inclined downward toward the reservoir *e*, this in order to 65 conduct excess lubricant to the reservoir in a manner that will be hereinafter set forth in detail. In one side of the lower casing section *a* are formed openings *g* which are disposed at opposite sides of the reservoir *e* and 70 are designed to be normally closed by doors *h*, arranged between and held in position by guides *h'*. These doors *h* are shown as sliding doors, but I would have it understood that they may be swinging doors or doors of 75 any other description without involving departure from the scope of my invention, as claimed. The upper casing section *b* is provided with a dome *i* disposed above the reservoir *e*, as shown in Figs. 1 and 2. 80

C is a drum journaled in suitable bearings in the reservoir *e* and provided by preference with end flanges as illustrated.

D is a belt, preferably of absorbent or porous material, passed around the shaft *A* 85 and the drum *C* and having for its office to convey lubricant from the reservoir *e* to the said shaft, and *E* is a roller, preferably of rubber or analogous material, arranged above the belt *D* and having trunnions journaled and movable vertically in the dome *i* 90 of the upper casing section, while *F* is a yoke carrying the said trunnions and adjustable up and down through the medium of screws *G* which bear in threaded apertures in the top of the dome *i* and are swiveled to the said yoke *F*. By turning the said screws *G* in one direction or the other, the pressure which the roller *E* exerts on the belt *D* to express lubricant from said belt may obviously 95 be increased or diminished at the pleasure of the party using my improvements. At this point it will be noted that by reason of the roller *E* bearing as stated against the belt *D* at a point above the shaft *A*, the said shaft 100 when rotated will be profusely lubricated from the belt which is caused to travel by the shaft.

H H are lubricant retainers. These retainers are each of the construction best 110

shown in Figs. 4 and 5, by reference to which it will be seen that they are curved in conformity to the shaft A and are provided with depending stems k. These depending stems k are disposed in sockets l rising from the bottom portions f of the lower casing section a and are mounted upon coiled springs m, the purpose of which is to yieldingly press the retainers against the shaft A with a view 5 of increasing the efficiency of said retainers. Because of the provision of the retainers H it will be seen that any excess lubricant that may find its way to points adjacent to the ends of the casing, will be caused by the retainers to leave the shaft A and pass down to the bottom portions f of the lower casing section to the reservoir e.

With a view of filtering the used lubricant during its said passage back to the reservoir e, 20 I provide the filters I, one of which is shown in Figs. 8 and 9. The said filters I respectively comprise a U-shaped portion p, preferably of sheet-metal, having right angle flanges r at its ends and also having openings 25 s in its sides, and suitable absorbent material t, cotton packing or cloth for instance, removably arranged in the said metallic section p. The said filters I are introduced through the openings g of the lower casing 30 section a so that they rest crosswise of the casing and on the bottom portions f of the lower casing section a, and so that their flanges r bear against the outside of said casing section a. Thus it will be seen that 35 when the doors h are closed they will rest against the flanges r and thereby hold the filters I in their proper working positions, while when the said doors h are opened, the operator may grasp the flanges r and readily 40 remove the filters I from the casing B in order that the packing of said filters may be replaced with fresh packing or for any other purpose. It will also be apparent that before the excess lubricant can find its way 45 back to the reservoir e it must pass through the openings s and percolate through the filtering material or packing t of the filters I. From this it follows that when it reaches the reservoir e, the lubricant will be robbed of 50 dirt and all other foreign substance collected during its passage over the shaft A, as is obviously desirable.

Removably arranged and held in the lower casing section a is a section J of Babbitt 55 metal or analogous material which is recessed at u to permit of the free passage of the belt D, and removably arranged and held in the upper casing section b and arranged over the end portions of the Babbitt metal section J 60 are Babbitt metal sections K. These latter and their arrangement relative to the shaft A and the section J are best shown in Fig. 6; the sections K being spaced in order not to interfere with the action of the roller E 65 against the belt D.

During the rotation of the shaft A arranged in my novel journal box, it will be apparent that the belt D is caused to travel and convey lubricant from the reservoir e to the top of the shaft A. It will also be apparent that the roller E will press lubricant from the upper portion of the belt D and cause such lubricant to spread over and thoroughly lubricate the bearing of the shaft in the Babbitt metal sections J and K. Such of the lubricant as finds its way outward beyond the Babbitt metal sections J and K will be taken from the shaft A by the retainers H and caused to pass to the bottom portions f of the lower casing section a. The said excess lubricant will pass down the said inclined portions f and after percolating through the filters I will pass to the reservoir e. By virtue of the filtration of the excess lubricant in the manner described, it will be seen that the liability of dirt or other foreign substance finding its way into the reservoir e is reduced to a minimum which is an important desideratum.

In addition to the practical advantages hereinbefore ascribed to my improved journal box, it will be noted that the said box is advantageous because of its compactness and the fact that it is well adapted to withstand the usage to which journal boxes are 90 ordinarily subjected.

The construction herein illustrated and described constitutes the preferred embodiment of my invention, but it is obvious that in practice such changes and modifications may be made as fairly fall within the scope of my invention as defined in the claims appended.

Having described my invention, what I claim and desire to secure by Letters-Patent, 105 is:

1. A journal box arranged to receive a shaft or the like and comprising a casing having a lubricant reservoir at an intermediate point of its length and bottom portions arranged at opposite sides of said reservoir and inclined downward to the same, means for conveying lubricant from the reservoir to the shaft, means for taking excess lubricant from the shaft and causing the same to pass to the inclined bottom portions of the casing, and lubricant filters extending across the inclined bottom portions of the casing at opposite sides of the lubricant reservoir.

2. A journal box arranged to receive a shaft or the like and comprising a casing having a lubricant reservoir and also having an opening at one side of said reservoir and a door for normally closing said opening and further having a bottom portion inclined downward to the reservoir, means for conveying lubricant from the reservoir to the shaft, means for taking excess lubricant from the shaft and causing the same to pass to the inclined bottom portion of the casing, and a lubri- 120 125 130

cant filter extending through the said opening of the casing and across the inclined bottom portion thereof and arranged to be removably retained in position by the door of the opening.

3. A journal box arranged to receive a shaft or the like and comprising a casing having a lubricant reservoir at an intermediate point of its length and bottom portions arranged at opposite sides of said reservoir and inclined downward to the same and also having openings at opposite sides of said reservoir and doors for normally closing said openings, means for conveying lubricant from the reservoir to the shaft, means for taking excess lubricant from the shaft and causing the same to pass to the inclined bottom portions of the casing, and lubricant filters extending through said openings of the casing and across the inclined bottom portions thereof and arranged to be removably retained in position by the doors of the openings.

4. In a journal box, the combination with a casing having a lubricant conduit and also having an opening in a wall of said conduit; of a lubricant filter removably arranged in said opening and across the lubricant conduit of the casing.

5. In a journal box, the combination with a casing having a lubricant conduit and an opening in a wall of said conduit and also having a door for normally closing said opening; of a lubricant filter removably arranged

in said opening and across the lubricant conduit of the casing and having flanges at its outer end arranged at the outer side of the casing and at the inner side of the said door to be retained in position by the latter.

6. The combination in a journal box, of a casing arranged to receive a shaft or the like and having a lubricant reservoir at an intermediate point of its length and bottom portions arranged at opposite sides of said reservoir and inclined downward to the same, a Babbitt metal section arranged in the casing and under the shaft and having recesses in its longitudinal edges, Babbitt metal sections arranged above the shaft and on the first mentioned section, a drum mounted in the reservoir, a belt passed around the shaft and the drum and through the recesses of the lower Babbitt metal section, means for exerting pressure against the portion of the belt on the shaft, lubricant retainers yieldingly pressed against the shaft within the casing and beyond the outer ends of the Babbitt metal sections, and filters extending across the inclined bottom portions of the casing.

In testimony whereof I have hereunto set my hand in presence of two subscribing witnesses.

ALBERT H. LEWIS.
